United States Patent Office

Des. 194,297
Patented Dec. 25, 1962

194,297

GATE VALVE

Marvin H. Grove, 340 Hillside Ave., Piedmont, Calif.

Filed Nov. 2, 1961, Ser. No. 67,360

Term of patent 14 years

(Cl. D78—1)

FIG. 1

Des. 194,297

PAGE 2

FIG. B.

FIG. 3.

FIGURE 1 is a perspective view of a gate valve showing my new design.

FIGURE 2 is a perspective view thereof as seen from the left of FIGURE 1.

FIGURE 3 is a perspective view thereof as seen from the opposite side of FIGURE 1.

I claim:

The ornamental design for a gate valve, substantially as shown.
